BRACKET FOR BATHROOM FIXTURES

Paul F. Simpson, Washington, Conn., assignor to The Autoyre Company, Inc., Oakville, Conn., a corporation of Connecticut

Application February 24, 1949, Serial No. 1,070

Term of patent 14 years

(Cl. D4—3)

To all whom it may concern:

Be it known that I, Paul F. Simpson, a citizen of the United States, residing in Washington, State of Connecticut, have invented a new, original, and ornamental Design for Bracket for Bathroom Fixtures, of which the following is a specification, reference being had to the accompanying drawing, forming a part thereof.

Fig. 1 is a perspective view of a bracket showing my new design, the said view illustrating the bracket in connection with a toilet tissue holder, the latter being illustrated in dotted lines;

Fig. 2 is a plan view of the bracket of Fig. 1, and

Fig. 3 is a front view of the bracket of Fig. 1.

The dominant features of my new design have been illustrated in the drawing in full lines.

I claim:

The ornamental design for a bracket for bathroom fixtures, substantially as shown and described.

PAUL F. SIMPSON.
